(57) CLAIM

The ornamental design for a vehicle spare wheel and tire carrier as shown and described.

DESCRIPTION

FIG. 1 is a front top left perspective view of a vehicle spare wheel and tire carrier according to the new design.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof.

FIG. 8 is a front top right perspective view thereof.

FIG. 9 is a front bottom right perspective view thereof.

FIG. 10 is a rear top left perspective view thereof.

FIG. 11 is front left perspective view of the vehicle spare wheel and tire carrier installed on a vehicle in a closed configuration.

FIG. 12 is a front right perspective view of the vehicle spare wheel and tire carrier installed on a vehicle in a closed configuration.

FIG. 13 is a front left perspective view of the vehicle spare wheel and tire carrier installed on a vehicle in an open configuration; and,

FIG. 14 is a top right perspective view of the vehicle spare wheel and tire carrier installed on a vehicle in an open configuration.

The portions of the vehicle spare wheel and tire carrier rendered in darker gray tones are claimed. The portions of the vehicle spare wheel and tire carrier rendered in light gray are for illustrative purposes and form no part of the claimed design.
